UNITED STATES PATENT OFFICE.

MICHAEL F. BROGAN, OF LAWRENCE, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

SIDE-LASTING MACHINE.

1,291,756.

Specification of Letters Patent.

Patented Jan. 21, 1919.

Application filed July 14, 1915. Serial No. 39,855.

To all whom it may concern:

Be it known that I, MICHAEL F. BROGAN, a citizen of the United States, residing at Lawrence, in the county of Essex and State 5 of Massachusetts, have invented certain Improvements in Side-Lasting Machines, of which the following description, in connection with the accompanying drawings, is a specification, like reference characters on the 10 drawings indicating like parts in the several figures.

This invention relates to lasting machines and is herein illustrated as embodied in a lasting machine of the type adapted to tension a shoe upper about a last progressively and secure the tensioned upper step by step to a shoe insole.

In the manufacture of welted boots and shoes, machines of the general type disclosed 20 in United States Letters Patent No. 1,011,592, granted Dec. 12, 1911, on an application of

W. J. Drey, and known to the trade as "Goodyear upper stapling machines", are extensively used to form and insert along 25 the sides of shoes a series of permanent staple fastenings through the upper and channel lip of an insole to replace the lasting tacks which were driven into the insole to secure the lasted upper temporarily in position in the preceding 30 lasting operation on the shoe. This procedure involves two independent operations on the shoe, namely, lasting and tacking the shoe, and then inserting the permanent staple fastening and removing the lasting tacks.

The present invention has for its principal object to provide a machine in the use of which said two operations of side lasting and staple fastening the upper can be combined, 40 thus effecting a considerable saving both in the labor and the cost of manufacture of the shoe.

In the illustrated embodiment of the invention the above and other objects are accomplished by providing a stapling machine, such for example as that disclosed in said Letters Patent, with a gripper arranged to seize the upper and coöperate with the staple fastening mechanism in such a manner that 50 the upper is tensioned about the last by the gripper and the tensioned upper wiped into position against the lip on the inner sole during the presentation of the shoe to the fastening inserting mechanism in position to re-

ceive a fastening. As herein shown, the 55 gripper is operated to seize the upper by means controlled by a manually effected movement of the staple clenching tool into operative position.

Other objects and features of the invention, including certain details of construction and more important combination of parts, will now be described in connection with the accompanying drawings and the invention will then be defined in the claims. 60 65

In the drawings:—

Figure 1 is a side elevation of a machine embodying the invention in a preferred form;

Fig. 2 is a plan view of the machine shown 70 in Fig. 1; and

Fig. 3 is a front elevation of a portion of the machine showing the position of the gripper with respect to the fastening clenching tool. 75

The machine in which the present invention is herein shown comprises staple forming mechanism and staple driving mechanism constructed and arranged to drive a fine wire staple through the upper and channel lip of an insole, and a clenching tool for clenching the staple upon the inside of the channel lip substantially like the machine disclosed in said Letters Patent, to which reference may be had for a complete description 80 of the construction and operation of the stapling mechanism. As in the machine of said Letters Patent the outside forming member of the staple forming and inserting mechanism carries with it a tucking tongue 85

2 which projects in front of the forming member and beyond the end of the lower portion of the nose 4 when the outside former has completed its staple forming operation so as to engage the upper just before the 90 staple is inserted and tuck it into the angle of union between the channel lip and the feather of the insole. The staple clenching tool or anvil 5, which also serves to clamp the work, is carried by a slide 6 arranged to 100 slide in a guideway 7 in a forked extension 8 of the machine frame. The slide 6 is connected by a link 10 and spring 11 to one arm 12 of a bell crank lever pivoted at 14 to the machine frame, the other arm 16 of the bell 105 crank lever being connected by a treadle rod 18 to a treadle (not shown) in the base of the machine. Depression of the treadle acts first

through the connections described to move the clenching tool 5 into work clamping relation to the nose 4 through which the staples are driven. Further depression of the treadle, permitted by the lost motion provided by the spring 11, actuates the clutch 22 to cause the staple fastening forming and inserting mechanism of the machine to operate in substantially the same manner as described in said Letters Patent.

In accordance with this invention a gripper is located in front and laterally of the stapler nose 4 and to one side of the clenching tool 5 (see Fig. 3). This gripper comprises coöperating jaws 24 and 26, the jaw 24 of which is rigidly mounted in a casing 28 pivoted at 30 to one side of the forked extension 8 of the machine frame. The coöperating jaw 26 of the gripper is mounted for vertical movement in guideways in the casing 28 and at its upper end 27 is provided with a stud 31 which is received in a longitudinally extending slot 32 in a lever 34 which is pivotally supported at its opposite end on a pin 36 in an upstanding lug 38 on the frame 8. This lever extends substantially parallel to the link 10 and between the said link and the upper end 27 of the jaw 26 as appears in Figs. 2 and 3. The side face of the lever adjacent to the link 10 is provided with a longitudinally extending curved cam slot 40 which receives a roll 42 mounted on the adjacent face of the link 10. It may be seen that endwise movement of the link 10 will oscillate the lever 34 and thereby raise or lower the jaw 26 of the gripper. The cam slot is appropriately shaped to insure prompt closing of the gripper during the early part of movement of the link 10. The jaw 26 is normally pressed upwardly by a spring 44 interposed between the top of the casing and a flange 46 on the shank of the jaw. In order to hold the closed gripper from bodily movement toward the stapler nose 4 and also to cause the gripper to pull the upper during the movement of the shoe into fastening receiving position, the casing 28 is provided with an extension 48 between the outer end of which and the machine frame a stiff compression spring 50 is interposed.

In the use of the machine above described the assembled shoe is presented to the machine so that the clenching tool 5 is positioned in the channel of the insole and the marginal portion of the shoe upper extends into the jaws of the gripper. Depression of the treadle causes the clenching tool 5 to be moved toward the stapler nose 4 through the link 10 which simultaneously oscillates the lever 34 and causes the jaw 26 of the gripper to be closed to seize the upper. As the shoe is moved by the clenching tool into fastening receiving position against the stapler nose 4 of the inserting mechanism, as shown in

dotted lines in Fig. 1, the shoe is carried horizontally away from the gripper and the upper is tensioned about the last yieldingly, the spring 50 resisting the tendency of the gripper to turn on the pivot rod 30 and follow the movement of the shoe toward the stapler nose. Upon further depression of the treadle the tensioned upper and the channel lip are finally clamped in fastening receiving position between the stapler nose 4 and the clenching tool 5 and the clutch is actuated to cause the machine to form and insert a fastening through the upper and channel lip of the insole, the fastening being clenched on the inside of the channel by the clenching tool. The gripper is preferably so controlled by the cam slot 40 that it retains its hold upon the upper until after the fastening operation so that additional tensioning of the upper is secured when the tucking tongue 2 engages the upper and tucks it into the angle of union between the channel lip and the feather of the insole.

The release of the treadle through its spring (not shown) returns the clenching tool 5 to its initial or inoperative position and opens the gripper whereupon the operation is repeated for lasting and staple fastening successive portions of the shoe. It will be noted that by utilizing the manually controlled movement of the clenching tool into operative position sufficient time may be taken to manipulate the shoe to secure the insertion of the fastening to the best advantage.

Having described my invention, I claim as new and desire to secure by Letters Patent of the United States:—

1. A machine of the class described, having in combination, a fastening inserting mechanism constructed and arranged to drive a fastening through the upper and the lip of an insole, a gripper for tensioning the upper, a clenching tool movable toward and away from said fastening inserting mechanism, and a single means for moving said clenching tool and operating said gripper.

2. A machine of the class described, having in combination, a fastening inserting mechanism constructed and arranged to drive a fastening through the upper and the lip of an insole, a gripper operative to seize the upper and to pull it about the last, means for clenching the fastening upon the inside of the channel lip, and manually controlled means for moving said clenching means toward the fastening inserting mechanism.

3. A machine of the class described, having in combination, a power operated fastening inserting mechanism constructed and arranged to drive a fastening through the upper and lip of an insole, a gripper for pulling the upper, means for clenching the

fastening upon the inside of the lip, and manually controlled means for moving said clenching means toward the fastening inserting mechanism as an incident to effecting the operation of the fastening inserting mechanism.

4. A machine of the class described, having in combination, a power operated fastening inserting mechanism constructed and arranged to drive a fastening through the upper and lip of an insole, a gripper for pulling the upper, means for clenching the fastening upon the inside of the lip, and manually controlled means for operating the gripper as an incident to effecting the operation of the fastening inserting mechanism.

5. A machine of the class described, having in combination, a power operated fastening inserting mechanism constructed and arranged to drive a fastening through the upper and lip of an insole, a gripper for seizing the upper, means for clenching the fastening upon the inside of the lip, and a single means constructed and arranged to move said clenching means toward said fastening inserting mechanism, to actuate said gripper, and to effect an operation of said fastening inserting mechanism.

30 6. A machine of the class described, having, in combination, a fastening inserting mechanism constructed and arranged to drive a fastening through the upper and lip of an insole and clench the fastening upon the inside of the lip, and a gripper arranged in position to seize the portion of upper that is to be fastened and to hold it while the shoe is moved relatively to the gripper into position to receive the fastening from said inserting mechanism.

35 7. A machine of the class described, having in combination, a fastening inserting mechanism constructed and arranged to drive a fastening through the upper and lip of an insole and clench the fastening upon the inside of the lip, a gripper arranged in position to seize the portion of upper that is to be fastened and to hold it while the shoe is moved relatively to the gripper into position to receive the fastening from said mechanism, and means for so moving the shoe to stretch the upper and then for causing the operation of said inserting mechanism.

40 8. A machine of the class described, having in combination, a fastening inserting mechanism constructed and arranged to drive a fastening through the upper and the lip of an insole, a gripper for seizing the upper, means for clenching the fastening upon the inside of the channel lip, and a single means for moving said clenching means toward the fastening inserting mechanism and for operating the gripper.

45 9. A machine of the class described, hav-

ing in combination, a fastening inserting mechanism constructed and arranged to drive a fastening through the upper and the lip of an insole, a gripper for seizing the upper, means for clenching the fastening upon the inside of the channel lip, means for moving said clenching means toward said fastening inserting mechanism, and a gripper operating connection between the means for operating said clenching means and the gripper.

10 10. A machine of the class described, having in combination, a fastening inserting mechanism comprising a nose arranged to guide the fastening through the upper and the lip of an insole, a gripper arranged to seize the upper to tension the same, and manually controlled means for clamping the parts to be united against said nose while the upper is being held by the gripper.

15 11. A machine of the class described, having in combination, a fastening inserting mechanism comprising a nose arranged to guide the fastening through the upper and the lip of an insole, a gripper arranged to seize the upper to tension the same, and manually controlled means, operative in properly timed relation with respect to the gripper, for clamping the parts to be united against said nose while the upper is being held by the gripper.

20 12. A machine of the class described, having in combination, a fastening inserting mechanism constructed and arranged to drive a fastening through the upper and the channel lip of an insole, means for moving the shoe toward said mechanism for clamping the parts to be united in position to receive a fastening, a gripper located to stretch the upper during such movement of the shoe, and means for actuating said gripper to seize and hold the edges of the upper during movement of the shoe into fastening receiving position.

25 13. A machine of the class described, having in combination, a fastening inserting mechanism constructed and arranged to drive a fastening through the upper and the channel lip of an insole, a gripper arranged for movement toward and away from said mechanism, means for resisting the movement of said gripper toward said mechanism, means for moving the shoe toward said mechanism, and means for operating the gripper to seize and hold the upper during such movement of the shoe.

30 14. A machine of the class described, having in combination, a fastening inserting mechanism constructed and arranged to drive a fastening through the upper and the channel lip of an insole, a gripper pivotally mounted for movement toward and away from said mechanism, means for maintaining said gripper normally away from said mechanism, means for moving

the shoe into fastening receiving position, and means for operating the gripper to seize and hold the shoe upper during such movement of the shoe.

- 5 15. A machine of the class described, having in combination, a fastening inserting mechanism comprising a nose arranged to guide a fastening through the upper and the lip of an insole, a gripper mounted for limited movement toward and away from said nose, means for maintaining said gripper normally away from said nose, means for clamping the parts to be united against said nose, means for actuating said clamping means, and connections between said actuating means and said gripper to cause said gripper to seize and hold the upper during movement of said clamping means into operative position.
- 10 16. A machine of the class described, having in combination, a fastening inserting mechanism comprising a nose arranged to guide a fastening through the upper and the lip of an insole, a gripper mounted for limited movement toward and away from said nose, means for maintaining said gripper normally away from said nose, means for clamping the parts to be united against said nose, means for actuating said clamping means, and means by which said gripper is actuated to seize and hold the upper during movement of the clamping means into clamping position.
- 15 17. In a machine of the class described, fastening inserting means, work clamping means, manually controlled means for effecting the operation of said work clamping means and arranged for further movement to actuate said inserting means, and an upper pulling gripper arranged to be operated by said manually controlled means during the work clamping operation.
- 20 18. In a machine of the class described, a fastening guiding nose, a clenching tool movable toward said nose and adapted to move the shoe with it toward the nose, a gripper arranged to seize the edge of the upper and hold it while the shoe is being moved by the clenching tool, and manually controlled means for operating the clench-

ing tool and the gripper in properly timed relation.

19. A machine of the class described, having, in combination, fastening inserting means constructed and arranged to drive a fastening through the upper and insole channel lip, means for clenching the fastening upon the inside of the channel lip, manually controlled means for moving said clenching means toward the fastening inserting means whereby the parts to be united may be clamped and the clenching means brought into operative position before the fastening inserting operation, and a gripper arranged to engage the edge of the upper and hold it during movement of the shoe by the clenching means into fastening receiving relation to the fastening inserting means.

20. A machine of the class described, having in combination, a gripper, means for closing the gripper upon the edge of a shoe upper, means for holding the closed gripper from bodily movement, and a fastening inserting mechanism arranged relatively to the gripper for inserting a fine wire staple through the upper and the channel lip of the shoe insole and comprising staple guiding and driving devices and a clenching tool adapted to engage the shoe on the inner side of the channel lip and move the shoe toward the staple guide and away from the gripper and hold the shoe for the staple inserting operation.

21. A machine of the class described having, in combination, mechanism constructed and arranged to insert staples through an upper and the lip of an insole, a staple clenching anvil occupying a shoe receiving position away from the staple inserting mechanism, a gripper located to receive the edge of the upper when the shoe is presented to the anvil, and means to move the anvil and the shoe engaged by it away from the gripper to tension the upper and into position for the stapling mechanism to fasten the upper.

In testimony whereof I have signed my name to this specification.

MICHAEL F. BROGAN.
